UNITED STATES PATENT OFFICE.

FRANK SPENO, OF ITHACA, NEW YORK.

RAILROAD-BALLAST CLEANER.

Application filed January 4, 1923. Serial No. 610,593.

My invention relates to a railroad ballast cleaner.

This invention eliminates the ordinary screening of ballast by hand labor, it saves a great deal of ballast, which has hitherto been thrown away with the dirt, and saves raising of track more than is necessary in order to bury the dirt and cinders to make the track look clean, in this way saving material, as the raising of the track necessitates the use of more stone to fill the tracks to the grade where they belong.

My invention scoops the ballast and dirt from the sides of the track at the ends of the cross-ties; separates all the dirt from the ballast, and casts the former outside of the track any distance that may be required, the stone going back into the track as clean as it originally comes from the quarry.

Ordinarily the cleaning of the ballast on a mile track requires thirty men per day for a period of one month. This machine will clean at least two miles of the ballast per day with the necessary labor for handling the machine which does not exceed five or six men at the most.

In addition to the above, it saves a great deal of ballast hitherto wasted, which is a large item in maintenance of a roadbed, and in actual cost to the railroads is greater than the cost of labor.

In the accompanying drawings:

Fig. 1 is a plan view;

Fig. 2 is a side elevation;

Fig. 3 is a front view looking rearward showing the scoops in operative position;

Fig. 4 is a rear view showing the scoops folded;

Fig. 5 is a section on the line 5—5 of Fig. 1;

Fig. 6 shows an alternative form of elevator.

The numeral 1 represents a railway car, preferably of special design and 2, the excavating scoops. These are supported on arms 3, which are pivoted to the beam of the car by means of the pins 4. These arms when in working position are held in grooves 3' as shown in Figs. 1 and 2. The scoops 2 might have conveyors 2a actuated by the material or by power.

The scoops are located on opposite sides of the car where they are held down to their work by bars 5. At the rear of each scoop, a

pit 6 is formed to receive the dirt and ballast as it is caught in the scoops 2 at the sides of the track with the slow forward movement of the car. The ballast travels up the incline of scoops by means of corrugated endless belts. Two spiral worms 7 extend from the bottom of the pit 6 upwardly, or converge toward the center, their function being to lift the material as it is scooped from the sides of the track and discharge it upon the incline 8 at the center of the car from where it drops into the pit 8', from where it is picked up by the buckets 9 of an inclined endless conveyor 10, which latter travels over rollers 11 through a casing 12, and discharges at the upper end into a rotary screen 13 mounted upon a shaft 14, and which rotary screen is inclined, as shown in Figs. 2 and 4, to a point where it reaches discharge spout 15, which distributes the cleaned ballast at the rear of the car in the center of the track, and through which rotary screen 13 fine dirt and cinders drop into hopper 16 and are discharged at any time and place required, down over the sides of the track by pipes 17 as shown in Figs. 1 and 2. The spout 15 might swing in the arc of a circle, or more than one might be employed to distribute the ballast.

The spiral worms 7 have gears 18 at the top. These mesh with worm gears 19 on the shafts 20, and each shaft 20 has beveled gears 21, 22, at its opposite ends. Each bevel gear 21 at the forward end meshes with a bevel gear 23 on the shaft 24, which latter is driven by a worm 25 on a shaft 26 from the gasoline motor 27, all of which transmission mechanism included by the numerals 18 to 26 inclusive is controlled by the operator through a clutch-lever 28.

In lieu of the worms 7, endless conveyors 7' could be used, as shown in Fig. 6.

The bevel gear 22 meshes with a bevel gear 29 on the transverse shaft 30. The bevel gear 29 drives the bevel-gear 32 on a vertical shaft 33, which has bevel gears on its upper end for driving shafts 33' and 36. Shaft 33' has a bevel gear 34 which meshes with a bevel-gear 35 on the shaft 14, which turns the screen 13.

A horizontal shaft 36 has a pulley 37 thereon, from which a belt 38 extends to a pulley 39 on the shaft 40, which drives the endless conveyor 10.

Thus all the moving parts are driven from the motor 27 simultaneously through the transmission mechanism, including not only the parts numbered from 19 to 26, but also 5 from 29 to 40.

It is the custom of railroads to clean the ballast periodically, usually every two years, and while so doing to replace worn out and rotted ties. With the use of my machine, the 10 ballast, dirt and cinders between the ties are shoveled out to the sides of the track, the car carrying the machine is pulled by the locomotive slowly upon the track, and this material is caught by the two scoops 2 and carried into the pits 6, thence is lifted 15 to the incline 8, from which it falls into the pit 8', from where it is conveyed upwardly by the buckets 9, and discharged into the rotary screen 13, which separates the cleaned ballast from the dirt, discharging the ballast 20 over the spout 15 to the middle of the track in a condition substantially as clean as ballast newly delivered from the quarry. The dirt and cinders drop through holes in the 25 screen into the hopper 16 below, from which it is carried off to the sides to any convenient point through the pipe 17.

Thus in a convenient and economical way the ballast is quickly and effectually cleaned 30 and re-deposited on the track in a minimum length of time, and with only enough laborers to clean the dirt and ballast from between the ties and to operate the machine.

When not in use, provision is made for 35 folding the scoops up at the sides, as shown in Fig. 4. Cables 42 are provided for this purpose. These pass over pulleys 43 supported on the central beam 44, and thence to the windlass 45 operated by an air-hoist 40 (or any convenient means for the purpose) 46, the air for the purpose being supplied from the air-tank 47. Air-cylinders 48 have pistons and piston-rods 49 therein which extend to the spiral worms for raising the latter 45 preparatory to the scoops being raised when folded in the vertical position shown in Fig. 4. These air cylinders are supplied with air from the air tank 47. Preliminary to raising the scoops, bars 5 are slid or 50 swung out of the way of the arms 3 of the scoop. Guide-ways 50 limit and guide the movement of the spiral worms when raised or lowered by the air-hoist 48.

It is understood that the car is pulled forward by the locomotive, forcing the scoops 55 into the ballast by the operation of the locomotive, the ballast in that way being forced back to the elevating means, from which place the elevators raise it, carrying it to the conveyor, and the conveyor to the screen, the elevating means, conveyor and screen being operated independently by motive power carried by the car.

I claim:

60 1. A ballast cleaning machine including

scoops at the sides thereof, conveyors associated with the scoops for conveying the material therefrom, means for moving said scoops upwardly out of their operative positions, and means for moving the conveyors 70 out of the path of the scoops prior to the movement thereof into inoperative positions.

2. A ballast cleaning machine including 75 scoops at the sides thereof, conveyors associated with the scoops and extending thereinto for conveying the material therefrom, means for moving said conveyors out of the scoops, and means for moving the scoops upwardly into inoperative positions.

3. A ballast cleaning machine including 80 scoops at the sides thereof, slidably mounted spiral worms associated with the scoops and extending thereinto, and means for moving the spiral worms out of the scoops.

4. A ballast cleaning machine including 85 scoops at the sides thereof, slidably mounted spiral worms associated with the scoops and extending thereinto, and means for sliding the spiral worms out of the scoops to permit the movement thereof into inoperative positions.

5. A ballast cleaning machine including 90 scoops at the sides thereof, slidably mounted spiral worms associated with the scoops and extending thereinto, means for sliding the 95 spiral worms out of the scoops, and means for moving the scoops upwardly into inoperative positions.

6. A ballast cleaning machine including 100 scoops at the sides thereof, slidably mounted spiral worms associated with the scoops and extending upwardly therefrom, a centrally located incline upon which said spiral worms discharge, a conveyor extending upwardly from said incline, a screen associated 105 with said conveyor and means for moving the scoops out of normal position.

7. A ballast cleaning machine including a 110 frame, scoops at the sides thereof, arms pivoted to the frame and supporting the scoops, means for raising and lowering the arms and scoops, said frame having grooves formed therein for receiving the arms, and means for holding the arms in their lowered position.

8. A ballast cleaning machine including a 115 frame, scoops at the sides thereof, arms pivoted to the frame and supporting the scoops, means for raising and lowering the arms and scoops, said frame having grooves formed therein for receiving the arms and having notches formed in the sides thereof, and bars in said notches above the arms for holding said arms in their lowered positions.

9. A ballast cleaning machine including 120 scoops pivotally mounted thereon, means for raising and lowering the scoops, slidably mounted rotatable spiral worms for lifting the material to the center of the machine as it is gathered by the scoops, and means for 125

raising said worms when the scoops are elevated.

10. A ballast cleaning machine including scoops pivotally mounted thereon, means for raising and lowering the scoops, slidably mounted rotatable spiral worms for lifting the material to the center of the machine as it is gathered by the scoops, and pneumatic elevators connected with the worms for raising said worms out of the way when the scoops are elevated.

11. A ballast cleaning machine constructed and arranged to travel on a track, and having pivotally mounted excavating scoops at 15 both sides, pits at the rear of the scoops, into which the material from the scoops passes, rotary spiral worms extending upwardly from the pits and converging toward the center of the machine, an incline upon which 20 these spiral worms discharge, the spiral worms slidably mounted, and independent means for raising and lowering the scoops and the spiral worms when the scoops are folded upwardly.

25 12. The combination with a car, scoops at each side thereof pivotally mounted, a windlass, pulleys, cables extending from the scoops around the pulleys to the windlass, means for operating the windlass to raise or 30 lower the scoops, slidably mounted rotatable spiral worms for lifting the material to the center of the machine as it is gathered by the excavating scoops, and means for raising said worms out of the way when the scoops 35 are folded upwardly.

40 13. A ballast cleaning machine having scoops at the sides thereof for scooping up ballast at the sides of the track, spiral worms extending upwardly from the scoops for carrying the ballast to the center of the machine, a screen, an endless conveyor for carrying the ballast to the screen, a hopper located below the screen for collecting the dirt from the ballast, discharging means connected with the screen and hopper, means for driving the spiral worms, the endless conveyor and screen, and means for raising 45

the scoops and spiral worms out of their normal positions.

14. A ballast cleaning machine including 50 scoops, conveyors associated with the scoops for conveying the material therefrom, means for moving the scoops into inoperative positions, and means for moving the conveyors relative to the scoops prior to the 55 movement thereof into inoperative positions.

15. A ballast cleaning machine including 60 scoops at the sides thereof, conveyors extending into the scoops for conveying the material therefrom and onto the machine, means 65 for moving the scoops out of their scooping positions, and means for moving the conveyors out of their operative positions in the scoops prior to the movement of the scoops into inoperative positions. 65

16. A ballast cleaning machine including 70 scoops at the sides thereof, conveyors extending into the scoops for conveying the material therefrom, means for moving the scoops out of their scooping positions, and pneumatic means connected with the conveyors for moving said conveyors out of their operative positions in the scoops prior to the movement of the scoops into inoperative 75 positions.

17. A ballast cleaning machine including 80 scoops, slidably mounted conveyors associated with the scoops, and means for sliding said conveyors relative to the scoops.

18. A ballast cleaning machine including 85 scoops at the sides thereof, slidably mounted conveyors extending into the scoops, and means for sliding the conveyors out of the scoops.

19. A ballast cleaning machine including 90 scoops at the sides thereof having pits therein, slidably mounted conveyors extending into the pits, pneumatic means for sliding the conveyors out of the pits, and means for moving the scoops into inoperative positions. 90

In testimony whereof I affix my signature.

FRANK SPENO.
